(57) **CLAIM**

The ornamental design for mixer bottle device, as shown and described.

DESCRIPTION

FIG. 1 is an top, right, front isometric view of a first embodiment of a transparent mixer bottle device in the closed configuration.

FIG. 2 is a bottom, left, rear isometric view of FIG. 1.

FIG. 3 is a front view of FIG. 1.

FIG. 4 is a right side view of FIG. 1.

FIG. 5 is a rear view of FIG. 1.

FIG. 6 is a left side view of FIG. 1.

FIG. 7 is a top view of FIG. 1.

FIG. 8 is a bottom view of FIG. 1.

FIG. 9 is a top, right, front isometric view of a first embodiment of a transparent mixer bottle device in the open configuration.

FIG. 10 is a bottom, left, rear isometric view of FIG. 9.

FIG. 11 is a front view of FIG. 9.

FIG. 12 is a right side view of FIG. 9.

FIG. 13 is a rear view of FIG. 9.

FIG. 14 is a left side view of FIG. 9.

FIG. 15 is a top view of FIG. 9.

FIG. 16 is a bottom view of FIG. 9.

FIG. 17 is a top, right, front isometric view of a second embodiment of an opaque mixer bottle device in the closed configuration.

FIG. 18 is a bottom, left, rear isometric view of FIG. 17.

FIG. 19 is a front view of FIG. 17.

FIG. 20 is a right side view of FIG. 17.

FIG. 21 is a rear view of FIG. 17.

FIG. 22 is a left side view of FIG. 17.

FIG. 23 is a top view of FIG. 17.

FIG. 24 is a bottom view of FIG. 17.

FIG. 25 is a top, right, front isometric view of an opaque mixer bottle device in the open configuration.

FIG. 26 is a bottom, left, rear isometric view of FIG. 25.

FIG. 27 is a front view of FIG. 25.

FIG. 28 is a right side view of FIG. 25.

FIG. 29 is a rear view of FIG. 25.

FIG. 30 is a left side view of FIG. 25.

FIG. 31 is a top view of FIG. 25; and,

FIG. 32 is a bottom view of FIG. 25.

(Continued)

The broken lines are included for the purpose of illustration of portions of the mixer bottle device that form no part of the claimed design.
